(57) **CLAIM**

The ornamental design for a booth, as shown and described.

DESCRIPTION

FIG. 1 is a perspective view of a booth showing our new design;

FIG. 2 is a rear view thereof;

FIG. 3 is a front view thereof;

FIG. 4 is a bottom plan view thereof;

FIG. 5 is a top plan view thereof;

FIG. 6 is a right side view thereof having a transparent right door;

FIG. 7 is a left side view thereof having a transparent left door; and,

FIG. 8 is an enlarged portion of a block inside the booth. The broken lines shown on the drawings depict portions of the booth that form no part of the claimed design.
